FENCE POST CAP

Howard J. Barber, Detroit, Mich., assignor to
Milan Aluminum Casting Company, Milan,
Mich., a partnership

Application March 23, 1950, Serial No. 8,715

Term of patent 14 years

(Cl. D28—1)

To all whom it may concern:

Be it known that I, Howard J. Barber, a citizen of the United States, residing at Detroit, in the county of Wayne and State of Michigan, have invented a new, original, and ornamental Design for Fence Post Cap, of which the following is a specification, reference being had to the accompanying drawing, forming a part thereof.

Figure 1 is a side elevation of a fence post cap showing my new design;

Figure 2 is a top plan view of said fence post cap;

Figure 3 is a side elevation, opposite from that of Figure 1, of said fence post cap; and

Figure 4 is a rear elevation of said fence post cap.

I claim:

The ornamental design for a fence post cap, as shown.

HOWARD J. BARBER.
